UNITED STATES PATENT OFFICE.

ROLAND L. HAY, OF LANCASTER, OHIO, ASSIGNOR TO FRICK & LINDSAY COMPANY, OF PITTSBURGE, PENNSYLVANIA, A CORPORATION OF PENNSYLVANIA.

PUMP VALVE.

1,426,073.

Specification of Letters Patent. Patented Aug. 15, 1922.

Application filed July 9, 1919. Serial No. 309,679.

To all whom it may concern:

Be it known that I, ROLAND L. HAY, a citizen of the United States, and resident of Lancaster, in the county of Fairfield and 5 State of Ohio, have invented a new and useful Improvement in Pump Valves; and I do hereby declare the following to be a full, clear, and exact description thereof.

My invention relates to working valves 10 used in connection with pumping of oil-wells.

These valves as constructed heretofore have consisted of a barrel, a head screwed into said barrel, and a crown screwed onto 15 the upper end of said head, the cups, rings and lock-nuts being interposed between the bottom head of said barrel and said head.

The object of my invention is to reduce the number of parts heretofore used to make 20 up these valves and so simplify the construction as well as the cost of production.

To these ends my invention comprises the novel features hereinafter set forth and claimed.

25 In the accompanying drawing Fig. 1 is a vertical elevation of my improved valve; Fig. 2 is a vertical section; and Fig. 3 is a cross-section on the line 3—3, Fig. 1.

In the drawing the numeral 2 designates 30 the barrel which is of uniform diameter with the bottom-head 3 formed integral therewith, said head consisting of the cage-like structure having the openings 4 for the admission of the fluid to the interior of the barrel.

35 Surrounding the barrel above the head 3 are the cups 5 and rings 6 of the ordinary construction which are tightened up and held fast between said head and the top ring 7 locked in place by the lock-nut 8.

40 The crown 9 is threaded interiorly as at

10 and is screwed onto the threaded portion 11 of the barrel, said crown having the shoulder 12 which fits down on the flange 13 of the valve-seat 14 and secures said valve in place. The ball 15 normally rests upon the 45 valve-seat 14. The lock-nut 16 is employed to prevent the unscrewing of the crown 9 when the pump is in use.

The crown 9 is hexagonal in cross-section for convenience in turning as indicated in 50 Fig. 3 and has the openings 17 to permit the escape of the fluid into the well.

By my invention I provide a valve body composed of only two parts, namely the barrel and the crown, thereby reducing the 55 number of parts to a minimum and obtaining a stronger construction. The rigid construction and simplicity of the valve gives it very important advantages over other valves composed of a greater number of 60 parts, and anything which will reduce the number of connected parts in a valve of this character which is used at such great depth insures more effective pumping.

What I claim is:

A working or pumping valve for oil-well pumps, comprising a barrel having a bottom-head integral therewith, a crown secured directly to the upper end of said barrel, cups and rings on said barrel, interposed between said head and a lock-nut engaging the uppermost of said rings, and a lock-nut on said barrel engaging the lower 70 end of said crown.

In testimony whereof, I, the said ROLAND 75 L. HAY, have hereunto set my hand.

ROLAND L. HAY.

Witnesses:
